UNITED STATES PATENT OFFICE.

ANDREW ALEXANDER, OF NEW YORK, N. Y.

PRINTING MACHINE.

1,427,569.

Specification of Letters Patent. Patented Aug. 29, 1922.

Application filed February 23, 1921. Serial No. 447,093.

To all whom it may concern:

Be it known that I, ANDREW ALEXANDER, a citizen of the United States, and a resident of New York city, in the county of Bronx 5 and State of New York, have invented new and useful Improvements in Printing Machines, of which the following is a specification.

This invention relates to improvements 10 in machines adapted for printing on the margin of sheets. The invention contemplates the production of a machine particularly adapted for printing the words of a song or the like on the margin of a roll 15 of perforated paper commonly known as a playing roll and used in connection with an automatic player piano, organ, or the like.

The general object of the invention is to simplify the operation of printing a roll 20 for player pianos and the like, and at the same time to reduce the cost of such printing operation to a minimum. To these ends the invention resides in a machine adapted for operating upon a plurality of corresponding 25 rolls simultaneously and thereby effect the printing of the words of a song or the like on these rolls in one operation.

Other objects will appear and will be better understood from that embodiment of the 30 invention of which the following is a specification, reference being had to the accompanying drawings forming part thereof, and in which

Fig. 1 is a contracted plan of the invention.

Fig. 2 is a front elevation of Fig. 1.

Fig. 3 is a detail elevation partly in section showing the spool holders and the device for applying an adhesive.

Fig. 4 is a detail section in plan on the line 4—4 of Fig. 3.

Fig. 5 is a detail and side elevation of the carriage disengaging means.

Fig. 6 is a detail partly in section and 45 elevation of the carriage and the engaging member.

Fig. 7 is a detail side elevation of the trimmer.

Fig. 8 is a detail perspective of one of the 50 elements of the endless type carrier.

Fig. 9 is a detail cross section of one of the type carrying elements with one of the type stamps connected thereto.

Fig. 10 is a detail perspective of one of the 55 type stamps.

Fig. 11 is a detail partly in section and

elevation showing the relation of the type stamp to the platen and the clutch for operating the platen.

Fig. 12 is a cross section on the line 12—12 60 of Fig. 11.

The device of this invention is intended for use in connection with the printing of a relatively large number or rolls, preferably 65 not less than 25 at one time. For this purpose the construction of one part of the machine will of course vary in size according to the capacity required for the machine, that is to say, according to the greatest number of rolls desired to be operated upon at one time. 70

Another portion of the machine, namely, that which carries the stamps of type will in point of size be constructed so that such type carrying part will be adequate for permitting the setting up thereon of the necessary 75 number of stamps of type needed for printing a predetermined number of the words of a song, composition or the like.

The roll carrying part of the machine designated generally by *a* consists of a suitable 80 number of supporting legs 5—5 of suitable height and disposed so as to support at a convenient distance above the floor, a base plate 6 which like the legs 5 may be formed of metal or other material having sufficient 85 stability and size to support the devices hereinafter to be described in connection with the roll carrying portion *a*. The type carrying portion *b* comprises a carriage frame or guide 7 which is supported by 90 the legs 8, the parts 7 and 8 being formed of metal or other suitable material and constructed so that the guide or carriage 7, will extend parallel with the base plate 6 but be disposed a trifle above the same. On the 95 side of the base plate 6 adjacent to the type carrying portion *b*, a series of bearings 9 are provided for the trunnions 10 of the platens 11, the surfaces of which are arranged in juxtaposition to the type carrier 100 *b* as shown in Fig. 1. The upper ends of the platens are provided with trunnions 12 which are journaled in bracket arms 13, secured to the upper sides of standards 15 which are secured or carried by the base 105 plate 6. The parts thus far described and those presently to be described are operated by a suitable motor (not shown) connected to suitable transmission devices which are in turn adapted to be connected 110 to the platens. In Fig. 2 the rack 16 is connected to the said motor and is keyed to a

vertical drive shaft 17, the lower end of which is disposed in a bearing 18 connected to a floor plate or the like, and the upper end of which is journaled in a bearing 19 carried by the end portion 20 of the guide 7. A bevel gear 20' keyed to shaft 17 meshes with a bevel gear 21 keyed to a shaft 22, journaled in bearings 23, secured to one end of the roll carrying portion *a*. A bevel gear 24 on shaft 22, adjacent to bevel gear 21, meshes with a bevel gear 25, on shaft 26 journaled in bearings 27 on the legs 5 adjacent to the type carrying part *b*. Collars 28, secured to shaft 26 abut the bearings 27 and prevent longitudinal movement of shaft 26 and in like manner the collars 29 on shaft 22 prevent longitudinal displacement of the said shaft in the bearings 23. Referring now to Figures 2 and 11, bevel gears 30 on shaft 26 mesh with bevel gears 31 secured to the lower ends of trunnions 10 which are tubular and support the platens 11. Face plates 32 on the lower ends of the platens 11 have recesses 33 aligning with the bores of the trunnions into which are adapted to be projected the clutch heads 34, one of which is shown in Fig. 11. The rod 35 secured to head 34 is surrounded by a compression spring 36 which bears on the shoulder 37 in the bore of the trunnion 10 and on a head 38 secured to the lower end of rod 35. The action of the spring normally holds the ends of a transverse pin 39 extending through the head 38 in the lower ends of a pair of oppositely disposed slots in the wall of trunnion 10, one of said slots being shown in Fig. 11, and indicated by 40. When in normal position, the head 34 is retracted from the recess 33 so that turning movement of shaft 26 and trunnion 10 is not transmitted to platen 11. Referring now to Figures 1 and 3, the end of shaft 22 remote from bevel gear 24 is provided with a bevel gear 40 which meshes with the bevel gear 41 secured to a shaft 42 disposed parallel with shaft 26 and arranged opposite thereto and journaled in bearings 43 secured to the legs 5. Collars 44 on shaft 42 prevent endwise movement of the shaft in the bearings 43. A plurality of bevel gears, one of which is shown in Fig. 3 and indicated by 45 are disposed substantially opposite to bevel gears 30 and secured to shaft 42. The bevel gear 45 shown in Fig. 3 meshes with the bevel gear 46 secured to one end of a tubular shaft 47, loose upon a spindle 48, the upper end of which is journaled in the overhanging portion 49 of a bracket 50 secured to the base plate 6 by bolts 51 or their equivalents passing through openings in lateral extensions 52 of the bracket as shown in Fig. 1. A tubular shaft 53 surrounds spindle 48 below overhanging portion 51 and is splined to the said spindle, this tubular shaft 53 forming one of the elements of a clutch, the other element of which is provided by the tubular shaft 47. These clutch elements normally engage so that rotary motion is imparted to the spindle 48 by the turning of shaft 42. The upright shank 54 of bracket 50 supports a T-shaped head, the stem portion 55 of which is provided with a bearing for the upper end of the spindle 56 which extends through and is secured to a bearing roll 57. As shown in Fig. 1, the bearing rolls 57 are disposed parallel with the platens 11 and substantially correspond therewith in point of size. The lower end of spindle 56 is journaled in an inwardly extending portion of the base plate of bracket 50 which base plate in contour conforms substantially to the contour of the T-shaped head 55. A flexible element 58 which may be a sprocket chain or a length of perforated fabric surrounds each of the platens 11 and the rolls 57 by being trained around reduced end portions 59—60, at the upper ends of each roll and platen. Teeth 61 in the extensions 59 and 60 engage with the openings of the flexible element 58 and thus the parts cooperate to impart rotation to the rolls 57. In Fig. 3, 62 designates a spool or bobbin of the type usually furnished with music rolls for player pianos and the like, and upon which the perforated paper is wound. The base 49 of bracket 50 is provided with a trunnion 63 which is received by an opening in the lower end of the spool 62, the upper end of which is recessed to receive a pin 64 extending through one end portion of the upper T-shaped head 55 and surrounded by a compression spring 65 which operates to force the pin 64 into the recess of the spool and thereby prevents disengagement of the parts under lateral pull on the spool. The pin 64 is provided with a milled head 66 which facilitates pulling the pin against the action of the spring in removing the spool or positioning the same in the bracket, as shown in Fig. 3. It being understood that the length of the spool will be greater than the normal distance between the terminals of the pins 63 and 64 in order that upward movement of the pin 64 against action of the spring 65 will take place in adjusting the spool to the position shown in Fig. 3. A winding spool 67 similar to the spool 62 and which will provide the bobbin or spool permanently combined with the finished music roll, is as shown in Fig. 3, positioned opposite spool 62 with its lower end in engagement with the upper end of the spindle 48 and its upper end engaged by a spring pressed pin 68 disposed in head 55, and corresponding in construction, disposition, and action, to the pin 64. Referring to Figures 1 and 2, the spools 62 and 67 are disposed substantially in opposite planes tangent to the platens 11 and the roll 57. In Fig. 1, the roll of paper 69 to be operated

upon is wound on the spool 62 and when the paper is directed from roll 57 and around platen 11, and connected to spool 67, the latter when operated from the shaft 42 and 5 spindle 48 operates to unwind the paper from the spool 62 and by the action of the spool 67, the paper will be wound thereupon. During this action on the part of the winder spool 67 it will be noted that the 10 platen will also rotate and likewise the roll 57, thus rolling surfaces are provided for the paper and friction reduced to a minimum.

It is proposed to eliminate the manual 15 operation which would ordinarily be required in connecting the end of the roll 69 to the spool 67 by training the said end around the platen and connecting it to the spool, and at the same time to provide means 20 which will prevent the paper from slipping during the operation of printing, when the inner end of the paper is disengaged from the spool 62. For this purpose suitable fasteners, an embodiment of which is shown in 25 Fig. 6 are provided and riveted as indicated by 70, or otherwise suitably secured at suitable intervals to the flexible element 58. The stationary jaw 71 of each fastener or 30 engaging element which is secured to the flexible element 58 is preferably of metal and relatively narrow and oblong and disposed upright or transversely with respect to the element 58. The projecting upper end of jaw 71 has a recess which receives 35 the movable jaw 72 which is connected by a pivot pin 73. The usual spring construction is associated with the pivot 73 for operating the jaw 72 to cooperate with the jaw 71 to clamp an element therebetween. The 40 upper end portion 74 of the jaw 72 is offset and constructed so as to cooperate with a trip 75 herein shown for purposes of illustration as a horizontally disposed plate formed of metal and substantially U-shaped 45 in contour and connected to the T-shaped head 55 or other suitable portion of the bracket 50. As shown in Fig. 5 side portions of the trip 75 slope downwardly as indicated by 76 and the terminal portions 50 as shown in Fig. 1, and indicated by 77 project upwardly and are disposed in the path of movement of the offset portion 74 of the jaw 72, and are so constructed as to deflect the offset portion and cause the same 55 to turn on the pivot 73 and by the sloping of the portion 76, to turn the jaw 72 into a substantially horizontal position. In Fig. 5, the location of the side portions of the trip 75 is such that a narrow space 78, exists 60 between the strip and the flexible element 58, and this space is such as to accommodate the offset portion 78 when the same is turned into a horizontal position. The terminal portions of the trip 75 correspond 65 and the trip is so constructed and disposed

that the extensions 74 when the flexible element moves in the direction of the arrow shown in Fig. 1 remain depressed from the time of engagement with one of the terminal portions of the trip, until moved by 70 the flexible element from engagement with the other terminal at which time the jaw 72 operating under the action of its spring moves to closed position. With this construction the operator is required only to engage the end of roll 69 with the fastener on the right in Fig. 1 nearest the trip 75 after which the succeeding trips will automatically engage the marginal portion of the sheet of paper as they emerge from underneath the trip and as the paper is carried by the movement of the endless element 58. It will be noted that the standard 15 is provided with lateral bearing surfaces in the form of rectangular plates 79 disposed between the rolls 57 and platens 11, and arranged substantially at a tangent thereto. With this construction bearing surfaces are provided for the sections of paper disposed between the platens and rolls in the movement of the paper from one spool to the other. 85 90

It is usual that the free end of the roll of perforated paper be substantially triangular shaped in contour so that the usual eyelet in the middle portion may be readily engaged with the take-off roll of the musical instrument. The present invention proposes to form the said end of the paper roll triangular after the printing operation and subsequent to the complete unwinding of the roll on the spool 62. In Figures 1, 2 and 7, vertical supports 80 are shown on the left of the platens in Figures 1 and 2, and adjacent the bearing plates 79, and each support, 95 as shown in Fig. 7 carries a triangular shaped cutting plate 81, the free ends of the side portions of which are rounded and elongated and bent inwardly and constitute pintles 82 which are journaled in brackets 83 secured to the support 80. Helical springs 84 surround the pintles and operate normally to hold the cutting edge of the cutter 81 in spaced relation to the adjacent bearing plate 79 on which is disposed a triangular shaped strip 85 secured to the plate by screws or their equivalents 86 and disposed so as to cooperate with the cutter 81 to permit the latter to cut as a shears. The normal width of the space between the cutter 81 and strip 85 will be sufficient to permit passage therethrough of the paper being wound by the spool 67. The cutting plate 81 is operated mechanically by a link 87 secured at one end to a point on the back of the plate and secured at its opposite end to a crank arm 88 connected to a crank 89, journaled in base plate 6, and provided at its lower end with crank arm 90 having a pin and slot connection with a lever 91 fulcrumed on the lower 100 105 110 115 120 125 130

face of the base plate 6 and having a pin and slot connection with a bell crank lever 91'. With this construction the turning of lever 91 rocks shaft 89 and turns link 87 which moves cutting plate 81 over the edge of plate 85. It is essential that there be no movement on the part of the endless element 58, platen 11, and roll 57, during the operation of the cutting plate 81 in order that the paper be at rest during the operation of the cutter; to accomplish this a lever 92 is provided and fulcrumed as indicated at 93, to the lower face of plate 6. One end portion of this lever is provided with an upwardly inclined surface 94 which is engaged by an arm of the bellcrank lever 91', when the lever 91 moves to operate the cutter 81. Engagement between the levers 91 and 92 operates to depress the end portion 94 of the latter, whereupon the opposite end portion 94 which is bifurcated and arranged in a groove 95 of the tubular shaft portion 53 is elevated and thereby the teeth thereon disengage from the teeth of the element 47. At the same time, and as shown in Figures 11 and 12, the forked end 96 of a lever 97 pivoted to a bracket arm 98 depending from the base plate 6 is depressed by the coil spring 36 in the trunion 37 and the head 33 disengaged from the platen 11, whereupon movement of the platen ceases. In Figures 11 and 12 it will be observed that the ends of the pin 39 extend into the groove in a ring 99 pivoted to the forked end portion 96 of the lever 97.

Referring now to Figures 1 and 2, the end of the guide 7 remote from the shaft 17 is supported by an upright 100 which is adjustably mounted on a base plate 101 provided with adjusting screws 102 for adjustably securing the upright longitudinally of the plate 101 and in a direction toward or away from shaft 17. A bearing 103 in a foot 104 of the upright 100 is provided for a shaft 105 which is also journaled in spaced bearings 107 and 108 at the ends of angularly disposed arms 109 at the upper end portion of the upright 100. A sprocket wheel 110 secured to shaft 105 between the bearings 107 and 108 is in alignment with a sprocket wheel 111 at the upper end portion of shaft 17. The sprocket chain 112 is trained around the sprocket wheels 110 and 111 and the adjustability of upright 100 provides for compensating for linear extension or contraction of the said chain. The chain 112 comprises the base of the type carrying portion of the machine and the type carrying elements 113 are pivotally connected to the said chain at one end. Each element 113 as shown in Fig. 8, is a channeled structure and formed of metal, and somewhat greater in length than the length of any of the links 115 of the chain 112. The links of the chain are receivable by the channels

114 of the elements 113 which latter have openings 115 in one end portion of their opposite sides 116 and 117 to receive the pivot pins connecting adjacent links of the chain 112. With this construction the elements 113 may turn on the pivots during the time that the links 115 move over the sprockets 110 and 111.

In the use of the present device, a stamp is prepared for each word to be printed on the margin of the music sheet, one of such stamps is shown in Figures 9 and 10 and comprises a base 118 formed preferably of rubber and provided on one face with a triangular face ribbed 119 which is insertable into a socket 120 formed by upstruck portions from the face 121 of the stock 122 which is preferably formed of a single piece of metal preferably U-shaped in contour and having inturned flanges 123 and 124 which are insertable into longitudinal grooves 125 and 126 in the sides 116 and 117 of the type carrying elements 113. The construction of the stocks 122 and the provision of the grooves 125 permit the stocks to be adjusted in the direction of the length of the elements 113, the resiliency of the metal of the stocks and the construction of the same permitting the stocks to frictionally engage the elements 113 and hold the stocks in any of their adjusted positions. With this construction an appreciable amount of pressure by the fingers on the part of the operator is required to move the stocks from one position of adjustment to the other on the elements 113, and the degree of contact between the stocks and the elements 113 will be sufficient to overcome any tendency from contact between the parts to displace the stocks as will hereinafter be described. It will be observed that the area of the stock is so proportioned with respect to the length of the element 113, a plurality of stocks may be arranged on each of the elements 113. This construction of course may be modified, it being obvious that the elements 113 may be proportioned to accommodate a greater number of stocks than shown in Fig. 1, or may be constructed so as to accommodate one stock. In any event the number of elements 113 provided for the chain 112 will be sufficient to accommodate enough stocks to provide for a predetermined number of words of a song which in ordinary cases will be the number of words included in several verses and choruses. It will be noted by reference to Figures 1 that a section of the chain 112 indicated in Figure 1 by 127 is exposed by reason that the combined lengths of the elements 113 is somewhat less than the total length of the chain. Referring now to Figures 1, 2, and 11, it will be observed that the arrangement of the type carriage is such that the stamps 118 make contact with the platens 11 when moved by 130

the chain to the inner side of the guide 7, as shown in Fig. 1. And the lower sides 116 of the elements 113 intercept the upper ends of the levers 97 and thereby depress the said 5 levers with the result that the heads 33 are engaged with the platens 11 and rotation transmitted to the platens by the gear connection previously described. It will be therefore, observed, by reference to Fig. 1, 10 that the elements 113 are disposed so that their ends substantially abut when arranged in alignment. This construction provides a substantially uninterrupted contact between the elements 113 and levers 97 shown in Figures 2 and 11 so that after the levers 97 have 15 been successively engaged the platens will rotate continuously until the exposed section 127 of the chain moves into alignment with the levers 97 at which time sufficient clearance will be afforded for the said levers by 20 reason of the absence of the elements 113 to permit springs 36 to depress the pins 35 and disengage the heads 33 from the platens 11, and thereby cause movement of the platens 25 in the parts connected therewith to cease. Reference now to Fig. 7 shows a pin 128 depending from the exposed portion 127 of the chain 112. The outer end portion of lever 91 extends into the path of movement 30 of the said pin. The pin is so positioned with respect to the series of levers 91 shown in Fig. 1, that the levers are successively engaged by the pins upon the levers 97 being released by the last element 113 carried by 35 the chain. The movement imparted to the levers 91 as these are successively engaged by the pin 128 operates the cutter 81 to engage and cut the sheet of paper as previously described. It will also be remembered that 40 during this operation of the cutter, the clutch elements for spool 67 are disengaged so that there will be no movement on the part of the paper being operated upon by the cutter. Referring now to Fig. 4, the lever 129 is pivoted as indicated at 130 to the lower face of 45 the base plate 6 and disposed so as to move horizontally. The pin and slot constructions 131 connect one end of lever 129 with the crank arm 132 connected to a vertically disposed shaft 133 disposed in the upright arm of the bracket 50. The upper portion of the shaft 133 terminates in a crank arm 134 which projects outwardly and is pivotally connected to a container 135 which is pivoted 50 to the bracket 50 and is provided with a lateral opening 136 and closed at its lower end and provided at its upper end with a removable cap 137. Normally the container is disposed in the space between the spools 62 and 67 and when the shaft 133 is turned, the crank arm 134 operates to tilt the container to the right in Fig. 3 and into contact 55 with the spool 67. The portion of the container making contact with the spool is at the opening 136 so that the adhesive flows

through the opening and onto the surface of the spool.

In the use of the device the usual preliminary of preparing a master roll is carried out. Stamps 118 are then provided 70 to correspond with the words printed on the master roll. The stamps 118 are then inserted into the keepers 120 of the stocks so that the words of the song will appear in the same relation as on the master roll. 75 It will be obvious that the words on the master roll will be spaced for various distances apart and corresponding spacing of the words on the type carrier may be effected by adjusting the stocks on the elements 113 as 80 previously described. When this adjustment of the parts has been made, the last word of the song will be on the end of the first element 113 on the outside of the type carrier in Fig. 1. The end of the roll 69 85 which is reversely wound on spool 62, is then taken and engaged with that clip on the flexible carrier nearest to the terminal of the side portion of the deflector on the right, in Fig. 2. It will of course be understood 90 that although this description is limited to engaging one of the rolls 69, it will be taken to apply to the other rolls disposed in the machine and the connection between the various rolls and their respective 95 clips will be made before the machine is set in operation. After engagement has been effected between the roll 69 and the clip, and the shaft 17 caused to turn by the action of the motor, movement of the chain 100 112 carries a pin 139 into contact with the projecting end of lever 129 whereupon the container 135 is tilted and an application of adhesive made to spool 67. Continued movement on the part of the flexible carrier 105 advances the sheet of paper from roll 69 to the platen 11 and then between the cutter, and finally to the spool 67 where the operator effects engagement by pressing the end of the sheet on the surface of the spool 110 which then by its rotation operates to wind the sheet of paper thereon.

When the perforations on the roll 69 opposite to the portion thereof to be printed move to the platen 11, first stamp 118 will 115 be then in position to impress said sheet and will then move to the adjacent sheet trained around the adjacent platen and so on until the various sheets have been impressed. By virtue of the adjustment of the stamps, 120 those succeeding the first stamp will impress the sheets at the proper time during the rotation of the parts. 141 indicates an ink feed roller arranged in a bracket 142 and in contact with a roller 145 arranged so 125 as to receive the ink from the roll 141 and apply the ink to the stamps prior to contact with the sheets. Although I have shown and described an ideal embodiment of the invention, it is to be understood that I am 130

not to be limited to the construction and arrangement of parts herein described, being obvious that mechanical changes within the scope of the claims without departing 5 from the spirit or sacrificing any advantage of the invention.

I claim:

1. In a printing machine a plurality of sets of parts, each comprising a perpendicular rotatable device, adapted for supporting a spool and winding a sheet of paper thereon, a support for the paper to be wound, arranged in spaced relation to the winding device and substantially parallel thereto, 10 and a platen for supporting the section of the sheet of paper between the spool and the support as the paper moves from the support to the spool, and a single type carrier cooperating with all of the platens to 15 print the sheets supported by them.
2. In a printing machine, a plurality of movable platens all of which are located in a plane coinciding with the plane of their movement, type carrying elements movable 20 bodily and successively into co-operative relation with said platens to form printing couples, and an endless elongated carrier for supporting the type carrying elements and moving them relatively to the platens.
3. In a printing machine, a plurality of rotatable devices, adapted for supporting a plurality of spools, and winding a plurality of sheets of paper thereon, a plurality of supports for the sheets of paper to be 25 wound, arranged in spaced relation to the winding devices, a plurality of platens for supporting the sections of the sheets of paper between the spools and the supports as the sheets move from the supports to the 30 spools, and a single movable type carrier constructed to co-act simultaneously with each of the platens to constitute a printing couple.
4. In a printing machine, a plurality of 35 rotatable devices, adapted for supporting a plurality of spools, and winding a plurality of sheets of paper thereon, a plurality of supports for the sheets of paper to be wound, arranged in spaced relation to the 40 winding devices, a plurality of platens for supporting the sections of the sheets of paper between the spools and the supports as the sheets move from the supports to the spools, a single, movable type carrier substantially equal in width to 45 one of the platens, said carrier having the type thereof arranged on a single line, and disposed so that the said type successively impress the portions of the sheets supported 50 by the platens and means for moving the type carrier in a plane intersecting all of the platens.
5. In a printing machine, a plurality of 55 rotatable devices, adapted for supporting a plurality of spools, and winding a plurality 60 of sheets of paper thereon, a plurality of supports for the sheets of paper to be wound, arranged in spaced relation to the winding devices, a 65 platen for supporting the section of the sheet of paper between the spool and the support as the paper moves from the support

of sheets of paper thereon, a plurality of supports for the sheets of paper to be wound, arranged in spaced relation to the winding devices, a plurality of platens for supporting the sections of the sheets of paper between the spools and the supports as the sheets move from the supports to the spools, and a movable type carrier, having the type thereof arranged on a single line, and disposed so that the said type successively impress the portions of the sheets supported by the platens successively. 70

6. In a printing machine, a rotatable device, adapted for supporting a spool and winding a sheet of paper thereon, a support for the paper to be wound arranged in spaced relation to the winding device, a platen for supporting the section of the sheet of paper between the spool and the support as the paper moves from the support to the 75 spool, movable means adapted for engaging the paper and carrying the same from the support to the platen, and a movable type carrier having the type thereof disposed in alignment, and arranged so that the 80 said type impress the portion of the sheet supported by the platen.

7. In a printing machine, a rotatable device adapted for supporting a spool, and winding a sheet of paper thereon, a support for the paper to be wound, arranged in spaced relation to the winding device, a platen for supporting the section of the sheet of paper between the spool and the support as the paper moves from the support to the 85 spool, and movable means adapted for engaging the paper and carrying the same from the support to the platen and directing the paper from the platen to the winding device. 90

8. In a printing machine, a rotatable device adapted for supporting a spool, and winding a sheet of paper thereon, a support for the paper to be wound, arranged in spaced relation to the winding device, a platen for supporting the section of the sheet of paper between the spool and the support as the paper moves from the support to the spool, movable means adapted for engaging the paper and carrying the same from the support to the platen and directing the paper from the platen to the winding device, and a movable type carrier having the type thereof disposed in alignment and arranged so that the said type impress the portion of the sheet supported by the platen. 100

9. In a printing machine, a rotatable device adapted for supporting a spool and winding a sheet of paper thereon, a support for the paper to be wound arranged in spaced relation to the winding device, a platen for supporting the section of the sheet of paper between the spool and the support as the paper moves from the support 105

to the spool, movable means adapted for automatically engaging the paper and carrying the same from the support to the platen and directing the paper from the platen to the winding device, and a movable type carrier having the type thereof disposed in a single line and arranged to impress the portion of the sheet supported by the platen.

10. In a printing machine, a rotatable device adapted for supporting a spool and winding a sheet of paper thereon, a support for the paper to be wound, arranged in spaced relation to the winding device, a platen for supporting the section of the sheet of paper between the spool and the support as the paper moves from the support to the spool, movable means adapted for engaging the paper and carrying the paper from the platen to the winding device, and automatically releasing the paper, and a movable type carrier having the type thereof disposed in a single line and arranged to impress the portion of the sheet supported by the platen.

25 11. In a printing machine, a rotatable device adapted for supporting a spool and winding a sheet of paper thereon, a support for the paper to be wound, arranged in spaced relation to the winding device, a platen for supporting the section of the sheet of paper between the spool and the support as the paper moves from the support to the spool, movable means adapted for engaging the paper and carrying the same from the support to the platen and directing the paper from the platen to the winding device, a cutter disposed so as to operate on the sheet of paper, and means adapted to be operated by the type carrier 40 to actuate the cutter to cut the sheet when the free end portion thereof is disposed between the winding device and the platen.

12. In a printing machine, a rotatable device adapted for supporting a spool and winding a sheet of paper thereon, a support for the paper to be wound arranged in spaced relation to the winding device, a platen for supporting the section of the sheet of paper between the spool and the support as the paper moves from the support to the spool, movable means adapted for engaging the paper and carrying the same from the support to the platen, and directing the paper from the platen to the winding device and automatically releasing the paper, a movable type carrier having the type thereof disposed in a single line and arranged to impress the portion of the sheet supported by the platen, a cutter arranged adjacent to the portion of the sheet disposed between the platen and the winding device and the cooperating structures carried by the cutter and the type carrier for operating the cutter to cut the free end portion of the sheet when the same is dis-

posed between the winding device and the platen.

13. In a printing machine, a rotatable device adapted for supporting a spool and winding a sheet of paper thereon, a support for the paper to be wound, arranged in spaced relation to the winding device, a platen for supporting the section of the sheet of paper between the spool and the support as the paper moves from the support to the spool, movable means adapted for engaging the paper and carrying the paper from the platen to the winding device, and automatically releasing the paper, a movable type carrier having the type thereof disposed in a single line and arranged to impress the portion of the sheet supported by the platen, a cutter arranged adjacent to the portion of the sheet disposed between the platen and the winding device and co-operating structures carried by the cutter and the type carrier for operating the cutter to cut the free end portion of the sheet when the same is disposed between the winding device and the platen, and means operated by the type carrier for stopping the movement of the winding device through operation of the cutter.

14. In a printing machine, a rotatable device adapted for supporting a spool and winding a sheet of paper thereon, a support for the paper to be wound arranged in spaced relation to the winding device, a platen for supporting the section of the sheet of paper between the spool and the support as the paper moves from the support to the spool, movable means adapted for engaging the paper and carrying the same from the support to the platen, and directing the paper from the platen to the winding device and automatically releasing the paper, a movable type carrier having the type thereof disposed in a single line and arranged to impress the portion of the sheet supported by the platen, a cutter arranged adjacent to the portion of the sheet disposed between the platen and the winding device and the cooperating structures carried by the cutter and the type carrier for operating the cutter to cut the free end portion of the sheet when the same is disposed between the winding device and the platen, means detachably connected to the winding device and the type carrier for operating the same, and means carried by the type carrier for disengaging the winding device from the said operating means during the operation of the cutter.

15. In a printing machine, a rotatable device adapted for supporting a spool and winding a sheet of paper thereon and support for the paper to be wound arranged in spaced relation to the winding device, a platen for supporting the section of the sheet of paper between the spool and the

support as the paper moves from the support to the spool, means for conveying the paper from the support to the platen and from the platen to the spool, a movable type carrier disposed so that the type thereof impress the portion of the sheet supported by the platen, a movable container carrying an adhesive and disposed adjacent to the spool of the winding device, and provided with a discharge opening disposed so

that upon movement of the container, adhesive will flow therefrom to the spool, and means operated by the type carrier for moving the container into contact with the spool, prior to the movement of the free end of the sheet into contact with the spool. 15

In testimony that I claim the foregoing as my invention, have signed my name hereunder.

ANDREW ALEXANDER.
